UNITED STATES PATENT OFFICE.

MABELLE HUNT, OF LOS ANGELES, CALIFORNIA.

COPYHOLDER.

Application filed September 29, 1925. Serial No. 59,276.

This invention relates to a copy-holder for holding copy before a typist. In copying from a book, and particularly from a bound volume, it is difficult to hold the exposed 5 pages of the book so that the marker can lie flat against them. This is due to the fact that when the book is supported in an open position, the line where its exposed pages are bound together will lie considerably to 10 the rear of the plane of the open pages.

The general object of this invention is to provide simple means for supporting a book for copying, so as to insure that both the exposed pages will be maintained substantially 15 in the same plane throughout their entire width; also to provide means for supporting the book, which can be readily adjusted to adapt it to the particular point in the book at which the pages are exposed.

20 A further object of the invention is to provide simple means for effecting a step-by-step downward movement of the marker as the copying proceeds, with means for operating the same from either side of the 25 copy-holder; also to provide simple means for guiding the marker and effecting its automatic return to an elevated position; also to provide means for regulating the amount of each step-by-step movement of 30 the marker, to adapt the same for use where the lines are different distances apart, for example, single spaced or double spaced.

35 Further objects of the invention will appear hereinafter.

The invention consists in the novel parts and combination of parts to be described hereinafter, all of which contribute to produce an efficient copy holder.

In the drawings:

40 Fig. 1 is a perspective of a copy holder embodying my invention, certain parts being broken away, or indicated in dotted outline.

45 Fig. 2 is a vertical section taken about in the plane of the line 2—2 of Fig. 1, and particularly illustrating details of the mechanism for advancing the marker-bar with a step-by-step movement, and for regulating the amount of its periodic movement.

50 Fig. 3 is a perspective illustrating further details and showing a portion of one of the cables with its dog supporting its adjacent end of the marker-bar.

In practicing my invention I provide 55 means supported in a frame, operating to lie

back of the open book and constructed so that it will hold the exposed pages of the book in substantially the same plane; I also provide a line marker movable down the front of the book, with means for guiding the same. At a suitable point, preferably at the lower and forward portion of the frame, I provide means for advancing the marker with a step-by-step movement.

In order to support the book, I prefer to 60 provide two rests, one of which supports the right side of the book, and the other the left side, and these rests are made movable so that as the copying progresses through the pages of the book, the right hand rest may be 65 moved forward at will, and the left hand rest may be moved backward at will, to accommodate the number of pages of the book located in front of each rest; this enables me to maintain the exposed pages of the book 70 substantially in the same plane. In addition to this I provide cables disposed respectively at each side of the frame for carrying the marker-bar, and associated with these cables I provide means operating when the marker 75 reaches the end of the page, to pull the cables back and return the marker-bar to an elevated position.

In order to accomplish this, I provide a 80 frame 1 constructed to rest upon a table. This frame has a large opening 1^a at the front, at which the exposed pages 1^b of the book, or other article being copied, is located. In order to insure that the exposed pages 85 1^b will be held in substantially the same 90 plane, I prefer to provide two backing plates 2 which are guided into position back of the pages; they may be slid downwardly into place through slots 1^c formed in the top plate of the frame.

95 In order to enable the marker to be advanced a fixed amount at each actuation, I provide a depressible member guided so as to have a limited amount of movement. For this purpose at the front and lower portion of the frame, and at each side of the same, I provide manually operated members, such as plungers or keys 3 which should be depressed after a line has been copied. Mechanism operated by these plungers will 100 move dogs 4 downwardly so as to carry the marker-bar 11 down the front of the book with a step by step movement. These plungers are returned by coil springs 3^a and operate to rotate the corresponding ratchet 105 110

wheels 5 through the medium of a pawl 14 pivoted to the lower end of the stem of the plunger. These ratchet wheels with the pawls 14, constitute a ratchet-and-pawl device for rotating a drum 6 which may extend all the way across the front of the frame.

When the drum is rotated it winds up cables 7 which extend up within the frame back 10 of the upright side-bars 1^a which form the sides of the opening 1^a. These cables are guided around suitable guide pulleys 10 on the frame, and suitable means is connected with their ends to exert an upright tension 15 in the cables at the front. For this purpose I prefer to provide a weight 8 attached to the rear end of each cable which hangs vertically down, and these weights may be guided in suitable guides 8^a which constitute the back legs of the frame.

A small spring 14^a is associated with each pawl 14 and holds it against the ratchet teeth.

The dogs 4 are rigidly attached to the cables 7 respectively, and each dog is in the form of a sleeve with a fin or plate 4^a which projects outwardly through a guide-slot 1^c which extends up along the corresponding side-bar 1^a.

30 A detent pawl 9 is provided which engages the teeth of one of the ratchet wheels 5, being held in an engagement with it, by a spring 9^a. By pressing down on the key 9^b this detent pawl may be released, whereupon the weights 8 will unwind the cables from the drum 6 and return the marker-bar 11 to an elevated position.

Back of the opening 1^a I provide two rests 12, one of them being at the left side, and 40 the other at the right. These rests are in the form of inclined plates, each plate having a flange 12^a at its lower end constituting a base, and resting upon the bottom plate 1^f of the frame.

45 Any suitable construction may be provided whereby, as the copying progresses through the book, the right hand rest may be moved forward, and the left hand rest may be moved backwardly to accommodate 50 the change in the number of pages at each side of the book. In the present instance I simply provide a plurality of sockets 12^b in the bottom plate 1^f and associated with each base plate 12^a I provide a pin 12^c which may fit into the proper socket to hold the book rest at the desired point.

It should be understood that even without the plates 2, the book-rests 12 can be so positioned that they will operate to hold the 60 exposed pages 1^b of the book in the opening 1^a, and in substantially the same plane with each other. However, I prefer to provide the backing plates 2 which slide into position back of the exposed pages and hold them 65 precisely in the same plane.

The frame 1 is left open on its rear side so as to permit the book to be put in place from the rear.

If desired the marker-bar 11 may be constructed so that it may be removably attached to the dogs 4. In order to do this, each end of the marker-bar 11 may be provided with a slot 11^a which fits into a corresponding slot 4^b cut in the upper edge of the fin 4^a.

75 In order to provide means for regulating the amount of movement given to the bar 11 after copying each line, I provide a stop-shaft 13 (see Fig. 2), which is rotatably mounted in the side walls of the frame and 80 provided on the outside of the case with a rotatable thumb-head 13^a. Under each pawl 14 this shaft is provided with a short arm forming a stop 13^b. In the position of the stops shown in Fig. 2 in full lines, the downward movement of the pawls 14 is unobstructed. This enables keys 3 to give the 85 drum 6 the maximum amount of angular rotation, which may correspond to a double spaced line arrangement. If the thumb-head 90 13^a is rotated towards the left, the stops 13^b will move into position under the pawls 14 as indicated by the dotted lines in Fig. 2. In this position the stops 13^b will 95 restrict the movement of the plungers 3 so that they can only move the stop bar through a single line space.

95 It is understood that the embodiment of the invention described herein is only one of the many embodiments this invention may 100 take, and I do not wish to be limited in the practice of the invention, nor in the claims, to the particular embodiment set forth.

What I claim is:

1. In a copy-holder for holding an open 105 book, the combination of a frame, means supported in the frame, operating to lie back of the two exposed pages for holding the same in substantially the same plane, a line marker, means for guiding the same at the front of the book, and means for advancing the marker with a step-by-step movement down the front of the book.

2. In a copy-holder for holding an open 115 book, the combination of a frame, means for supporting the book, a pair of plates supported in the frame operating to lie back of the two exposed pages for holding the same in substantially the same plane, a marker-bar extending across the exposed pages, 120 means for guiding the same at each side, and means for advancing the marker-bar with a step-by-step movement down the front of the book.

3. In a copy-holder for holding an open 125 book, the combination of a frame, means supported in the frame and operating to lie back of the exposed pages for holding the same in substantially the same plane, a line marker, means for guiding the same at the 130

front of the book, means for advancing the marker with a step-by-step movement down the front of the book, and means for returning the marker to an elevated position.

5. In a copy-holder, the combination of a frame, a pair of rests constructed to receive the flaps of the cover of an open book, means for holding the rests in different positions so as to maintain the exposed pages of the 10 book in substantially the same plane, a line marker and means for guiding the marker down the exposed pages.

5. In a copy-holder, the combination of a frame having a front opening, means for supporting the page to be copied at the front opening, a marker-bar extending across the front opening, said frame having means located at each side of the opening for guiding the marker-bar, means for moving the 20 marker-bar downwardly with a step-by-step movement, a cable at each side of the frame connected with the marker-bar and guided on the frame, returning means connected with each cable and exerting force in a direction to pull the marker-bar upwardly, and detent means for normally preventing the operation of said returning means, constructed to be released at will to permit the marker-bar to return to an elevated position.

6. In a copy-holder, the combination of a frame having a front opening, means for supporting an open book in the frame back of the opening with its exposed pages in the 25 opening, and a pair of plates guided in the frame operating to slide into position back of the exposed pages at the front of the book, and a marker guided to move down the front of the book.

40 7. In a copy-holder, the combination of a frame having a front opening, means for supporting an open book in the frame back of the opening, means for holding the exposed pages of the book substantially in the same plane, a marker-bar extending across the front opening, cables connected respectively with the ends of the marker-bar, guided on the frame, a ratchet-and-pawl device, with means controlled thereby for winding 45 up the cables to advance the marker-bar with a step-by-step movement downwardly, a detent pawl cooperating with the ratchet-and-pawl device to hold the marker-bar in any position to which it has been advanced, and means connected with the cables for 55 returning the marker-bar to an elevated position when the detent pawl is released.

8. In a copy-holder, the combination of a frame with upright side-bars at the front, means for holding the page to be copied in position between the side-bars, dogs guided respectively along the side-bars, cables disposed respectively adjacent the side bars and carrying the dogs, means for winding up the 60 cables with a step-by-step movement to ad-

vance the marker-bar down the page, detent means for holding the marker-bar in any position to which it has been advanced, and means associated with the cables for returning the marker-bar to an elevated position when the detent device is released.

5. In a copy-holder, the combination of a frame with upright side-bars at each side having slots respectively therein, means for holding a page to be copied in position between the side-bars, cables disposed respectively adjacent the side-bars, dogs carried respectively by the cables and extending through the slots, a marker-bar supported on the dogs, a drum with means for rotating the same with a step-by-step movement to wind up the cables, detent means for holding the marker-bar in any position in which it has been advanced, and means associated with the cables for returning the marker-bar to an elevated position when the detent means is released.

10. In a copy-holder for holding an open book, the combination of a frame, a right hand book-rest supported in the frame for supporting the right hand side of the open book, a left hand book-rest operating to support the left side of the open book, said right hand book-rest being movable toward the front and said left hand book-rest being 95 movable toward the rear to enable the exposed pages at the front of the book to be maintained in substantially the same plane, a marker with means on the frame for guiding the same down the book, and means for 100 controlling the marker.

11. In a copy-holder for holding an open book, the combination of a frame, a right hand book-rest supported in the frame for supporting the right hand side of the open book, a left hand book-rest operating to support the left side of the open book, said right hand book-rest being movable toward the front and said left hand book-rest being 105 movable toward the rear to enable the exposed pages at the front of the book to be maintained in substantially the same plane, a marker with means on the frame for guiding the same down the book, means for controlling the marker, and a pair of plates 110 guided in the frame to come into position back of the exposed pages and operating to maintain the exposed pages in substantially the same plane.

12. In a copy-holder, the combination of a frame having upright side-bars, cables associated respectively with the side-bars, a marker-bar supported on the cables, a drum at the front and lower portion of the frame for winding up the cables, a depressible member having a limited amount of movement for rotating the drum with a step-by-step movement to take up the cables and move the marker-bar downwardly, a detent pawl and ratchet associated with the drum for 125 130

holding the marker-bar in any position to which it has been advanced, means for guiding the cables along the frame, and means connected with the ends of the cables for exerting tension in the same and operating to return the marker-bar to an elevated position when the detent pawl is released.

13. In a copy-holder, the combination of a frame having upright side-bars, cables associated respectively with the side-bars, a marker-bar supported on the cables, a drum at the front and lower portion of the frame for winding up the cables, means for rotating the drum with a step-by-step movement 10 to take up the cables and move the marker-bar downwardly, a detent pawl and ratchet associated with the drum for holding the marker-bar in any position to which it has been advanced, means for guiding the cables along the frame, and weights connected 15 with the ends of the cables and guided on the rear of the frame for exerting tension in the cables, and operating to return the marker-bar to an elevated position when the detent pawl is released.

14. In a copy-holder, the combination of a frame, means for supporting the article to be copied in the frame, a marker-bar guided on the frame, cables guided on the 20 frame and carrying the marker-bar, a drum mounted at the front and lower portion of the frame for winding up the cables to move the marker-bar downwardly, and a ratchet wheel at each side of the frame, and rigid 25 with the drum, a hand-operated key at each side of the frame with a pawl cooperating with its corresponding ratchet wheel to rotate the drum and move the marker-bar.

15. In a copy-holder, the combination of 30 a frame, means for supporting the article to be copied in the frame, a marker-bar guided on the frame, cables guiding on the frame and carrying the marker-bar, a drum mounted at the front and lower portion of the frame for winding up the cables to move 35 the marker-bar downwardly, a ratchet wheel at each side of the frame, and rigid with

the drum, a hand-operated key at each side of the frame with a pawl cooperating with its corresponding ratchet wheel to rotate the 50 drum and move the marker-bar, a detent pawl associated with one of the ratchet wheels for holding the marker-bar in any position to which it has been advanced, and means associated with the cables for returning the marker-bar to an elevated position when the detent pawl has been released. 55

16. In a copy-holder for holding an open book, the combination of a frame, a pair of book-rests mounted in the frame respectively 60 supporting the cover-flaps of the books, said frame having a bottom plate supporting the rests, and having a plurality of sockets extending in a front and rear direction, and a removable pin corresponding to each book-rest and cooperating with the sockets to hold the rests in any adjusted position.

17. In a copy-holder, the combination of a frame, means for holding the article to be copied in the frame, a marker-bar extending 70 across the front of the frame, cables disposed respectively at the side of the frame and carrying the marker-bar, means for guiding the cables on the frame, a drum at the front and lower portion of the frame for 75 winding up the cables, a ratchet wheel carried by the drum at each side of the frame, a depressible plunger carried by the frame at each side and having a pawl for engaging its corresponding ratchet wheel, and co-operating with the drum to wind up the cables and move the marker-bar downwardly, a transverse stop-shaft mounted in the frame 80 below the plungers, and carrying stops movable into position to cooperate with the 85 plungers to limit their downward movement and enabling the plungers to rotate the drum through different predetermined angles, and thereby adapting the marker for double spaced lines or single spaced lines. 90

Signed at Los Angeles, California, this 23d day of September, 1925.

MABELLE HUNT.
